DUMP WASHER

William P. Beattie, Norwood, and George W. Johnson, Cincinnati, Ohio, assignors to The American Laundry Machinery Company, Norwood, Ohio, a corporation of Ohio

Application April 4, 1933, Serial No. 664,388

7 Claims. (Cl. 68—18)

This invention relates to laundry washing machines of the type which comprises as its principal parts a perforate work container mounted for reversing rotation on a fixed axis, and a liquid-receiving tub for said container wherein the detergent liquid is so disposed that the work in the rotating container is alternately submerged and withdrawn from the liquid.

More particularly this invention pertains to such apparatus wherein the tub is arranged for adjustment about the cylinder for convenient loading and unloading of the latter and for quick draining of the tub. Such general type of machine is exemplified in the patent to White, No. 1,775,879 of September 16, 1930, and the objects of this invention are generally to provide improvements on the arrangement there shown.

More particularly an object of the invention is to provide that operation of the parts be automatic so far as possible, under the control of the operator, so that the latter will be relieved of unnecessary labor and the operation of the machine speeded up yet without danger to the operator.

The exact nature of the invention together with further objects and advantages thereof will be apparent from the following description taken in connection with the accompanying drawings, in which Fig. 1 is a front elevation of a washing machine embodying the invention; Figs. 2 and 3 are right and left end elevations of the same; Figs. 4 to 7 are conventionalized showings as in typical transverse section through the machine, illustrating its manner of operation, Fig. 4 showing the parts as during the washing operation, Fig. 5 as in loading, Fig. 6 as in draining, and Fig. 7 as in unloading; Fig. 8 is a sectional elevation in the axial plane of the machine illustrated Figs. 1-3; and Fig. 9 is a wiring diagram of the electrical means employed for control and drive of the machine.

With reference now to the drawings, 1 is the work container or washing cylinder and 2 the tub therefor.

45 The cylinder 1 has a pair of imperforate end walls, the cylindrical wall between which is foraminous as usual in the art. The cylinder here shown is known as the Y compartment type, having radially disposed partitions 3 dividing the cylinder into three longitudinally extending compartments 4 of equal size. For each compartment a sliding door 5 is provided with a corresponding opening, by which arrangement the compartments may be closed as in Fig. 4, or their doors 55 opened for loading and unloading as in Figs. 5

and 7. As indicated Fig. 8, the cylinder 1 is mounted for rotation about its axis, in a base or frame 6, the cylinder having stub shafts 7 bearing in the base.

That the cylinder may be rotated, a gear 8 is secured upon the projecting end of each stub shaft, and a reversing motor 9 has driving connection with both the gears 8 through any suitable gearing such as that indicated Figs. 1-3.

The tub 2 is cylindrical, disposed coaxially of the cylinder 1 and mounted on the frame 6 for adjustment about its axis as by the end bearings at 10. The tub has a loading and unloading opening controlled by a door or doors 11 mounted for circumferential sliding movement as indicated Figs. 4-7, and longitudinally coextensive with the door-controlled openings of the cylinder and all of these openings preferably extending substantially the full length of the container cavities which they serve.

As to circumferential extent of the doors, since the cylinder has three equal compartments each subtending 120°, each compartment door 5 is 60° and moves 60°, while the tub door means 11 preferably is arranged to provide 120° of opening.

The tub is also provided with a relatively narrow longitudinally extending drain opening 12 so located with respect to the tub loading and unloading opening that both openings lie preferably on the same side of a diametrical plane, or at least as close together as consistent with the requirement that when the tub is in washing position as in Fig. 4, both openings are disposed well above the desirable level of the detergent or rinsing liquid in the tub.

That there be no loss of the liquid from splash during the washing operation, a stationary cover 13 is provided for registry overlying the opening 12 when the tub is in washing position. Preferably the cover 13 forms a part of a shield 14 which extends downwardly to a mouth 15 at the bottom of the apparatus adapted to discharge into a suitable drain. Thus when the tub is adjusted backward, clockwise from the position of Fig. 4 to the draining position, Fig. 6, the liquid 45 will be discharged from the tub, whence it will flow away within the shield 14 to the drain. The opening 12 extending the full length of the tub, the tub will be quite emptied of liquid by the time it reaches the position of Fig. 6 so that it 50 may be immediately returned to the next desired position.

The tub may be adjusted forwardly from its washing position to the dumping position illustrated Fig. 7, in which the contents of any of 55

the compartments 4 whose door 5 is open and which may be disposed forwardly as at 4a, will be discharged by gravity.

That the tub may be adjusted between its described positions, a segmental gear 16 is secured thereon as at one end, and a motor 17 arranged to drive the gear 16 through any suitable gearing such as that illustrated. That washing liquid may be supplied to the tub, and quickly, piping 18 is arranged to deliver through openings 19 in the base 6 at both ends of the tub; and that the entering liquid be kept clear so far as possible from the cylinder and tub bearings, pipes 20 are arranged to lead from the passages 19 downwardly as shown Fig. 8.

Both cylinder and tub are operated by power, each by its own driving motor, control of both motors being semi-automatic, subject to the will of the operator, and also for safety subject to certain interlocking arrangements to be described.

The cylinder-driving motor 9 has an associated casing 21 within which are located some of its control switches including an automatic reversing drum contact mechanism 21' timed with the motor as by any suitable connection including the chain drive indicated at 22'. The cylinder-reversing mechanism is indicated Fig. 9, and the arrangement as later described in greater detail will be recognized by one familiar with the art, as adapted to effect periodic reversal of the cylinder during the washing operation. A motor brake indicated at 23 may be included in the control means for maintaining the cylinder position when its motor is off.

A switch 24 is provided, and arranged to be automatically closed when the tub doors are fully closed, and to be otherwise open. This switch 24 is in circuit with a two-button stop and start switch 25, which is a control circuit for placing the cylinder in automatic reversing operation. The arrangement is such that both switches 24 and 25 must be closed before the cylinder may have operation. 25 is thus a hand-operated switch by which the operator may initiate automatic cylinder-reversing operation by placing the switch in the full-line position of Fig. 9, but only if the tub doors be fully closed.

26 is an automatic self-closing switch arranged to be held open only when the tub doors are fully closed as shown in Fig. 1. It is in series circuit with the start-stop switch 25 so that its circuit may be closed only when the switch 26 is in stop position (broken lines, Fig. 9) and thus the cylinder stationary. When the switch 26 is closed it places the push button switches 27, 28 and 29 in circuit for hand control of the cylinder drive motor 9 for operation of the latter to move the cylinder subject to hand operation and manipulation of the switches 27, 28 and 29. Switches 27 and 28 are placed in circuit through drum contacts 30 and 31. These hand-operated switches are located in a control board convenient to the operator at the front of the machine as shown Figs. 1 and 2.

The switches 27 and 28, when either is depressed, cause actuation of the cylinder drive motor to index the washing cylinder to the position of Fig. 5; and thereafter when the other is depressed the cylinder will be caused to move counterclockwise 60°. These switches 27 and 28 have associated timed cut-out switches 33 and 34 located in the controller casing 21 for the motor 9; the arrangement being one whereby, by alternate operation of the switches 27 and 28,

the washing cylinder may be caused to advance step by step one-sixth revolution at a time, and the timing of the cut-out switches being such that the first step of advance will properly index the cylinder as described, all as will be apparent to one familiar with the art.

Switch 29 is an emergency switch whereby the cylinder may be operated in reverse direction in case of accident, though the tub doors be open.

Adjustment of the tub through the operation of its motor 17 is controlled as follows: A cam 33 is secured upon the tub for actuating engagement, as the tub moves, with the operating levers of a number of automatic switches 34, 35, 35' and 42, mounted on the base frame 6 and shown Figs. 2 and 9. A push button switch 32 provided on the control board of the machine is arranged to effect closing of the circuit of the tub drive motor 17 to move the tub forwardly, clockwise, from the washing position of Fig. 4 to the drain position Fig. 6. As the tub attains the drain position its cam 33 engages the actuating lever of the switch 34 to open this normally closed switch. Switch 35 is biased toward closed position but is held open when the tub is in normal washing position as shown in Fig. 2. Switch 35 closes as soon as the tub leaves this position to set up a circuit (later described) by which the motor 17 automatically reverses and returns the tub counterclockwise from draining position. As the tub resumes its washing position the cam 33 engages the switch 35 to open its circuit and stop the tub.

A push button switch 41 is also provided on the control panel, in the circuit of the tub-actuating motor 17. This switch effects adjustment of the tub from loading position, that of Fig. 5, to dumping position, that of Fig. 7. As the tub attains dumping position, following operation of the push button 41, its cam 33 engages the actuating lever of the switch 42, opening the motor circuit and thus automatically stopping the tub in dumping position.

A push button switch 43 is provided in the tub motor circuit for returning the tub from dumping position to loading position. Closing of the switch 43 by depressing its button causes reverse operation of the tub motor to move the tub clockwise. Following this motion, as the tub attains loading position, that of Figs. 2 and 5, the cam 33 engages the actuator of the switch 35' to open the latter and thus automatically stop the tub.

As will be appreciated by one familiar with the art and as is indicated Fig. 9, the described operator-operated push button switches are in control circuits and not in the main motor circuits. The usual line cut-out switches 33 are provided and a safety switch 52 is preferably located on the control board for convenient reach by the operator to stop all motor operation in emergency.

Operation will be as follows, commencing with the cylinder empty, its compartment doors and the tub doors open and the parts otherwise positioned as in Fig. 5.

The near compartment is loaded with work and its door 5 closed. Push button switches 27 and 28 are next successively closed to rotate the cylinder forwardly in two steps of 60° each, bringing the next compartment into registry with the tub opening. This second compartment is loaded, its door closed, and the same procedure followed in loading the third compartment. The cylinder is then completely loaded.

Detergent liquid having been introduced into the tub to the proper level, by way of the pipe 18, the tub doors 11 are closed. This closes the switch 24 in the cylinder motor circuit, opens 5 the switch 26, and the cylinder is started in its automatic reversing operation in the washing cycle by throwing the switch 25 to the full line position of Fig. 9.

The work in the several compartments is tumbled about, successively submerged and raised 10 from the liquid as in the usual manner of operation of washing apparatus having this type of cylinder. During the washing operation changes 15 of liquid as from detergent to rinsing liquid, are made by the operator's depressing the drain button 32. When the tub is in washing position splash caused by cylinder operation does not result in loss of liquid because the drain opening 12 is closed by the cover 13. Depression of 20 the drain button causes rotation of the tub from the position of Fig. 4 to that of Fig. 6, with automatic return to that of Fig. 4, the cylinder continuing in its automatic operation during this tub adjustment. Each such tub adjustment effects 25 drainage of the tub liquid, which is replaced by new liquid through the pipe 18.

After the washing operation, the cylinder is stopped by throwing the switch 25 to the broken line position of Fig. 9. The tub doors 11 are next 30 fully opened to the position of Fig. 5, which automatically opens the switch 24 so that the cylinder cannot be restarted into automatic operation, and closes switch 26 in the forward operating circuit of the cylinder motor subject to the push 35 button switches 27, 28 and 29. Depression of the switch 27 adjusts the cylinder forwardly or counterclockwise, Figs. 4 to 7, until its nearest compartment registers with the tub opening, and consequently until the door 5 of such compartment, 40 which is then closed, registers with the lower or forward half of the tub opening as in Fig. 5. This compartment door is then opened by the operator.

The tub is next adjusted to the position of Fig. 45 7 by depression of the push button switch 41. Depression of the switch button 27 or 28 now causes 60° advance of the cylinder from the position of Fig. 5 to that of Fig. 7 which permits the work in the near compartment to slide out- 50 wardly through the door opening of the compartment into suitable means provided for transporting the work away from the machine. The other push button 27 or 28 is next depressed causing 60° advance of the cylinder to bring 55 its next compartment to the position of Fig. 5. After opening of the door of this second compartment the cylinder is again advanced, as in the case of the first compartment and its load permitted to be discharged by gravity. The third 60 compartment is emptied in the same manner, leaving the parts as in Fig. 7 and the machine ready to be reloaded for the next washing operation. This completes the cycle of the machine.

The control circuits through which the machine 65 is operated in the normal operating cycle are as follows:

Assume the machine loaded, the doors closed and therefore the interlocking switches completing the circuits for which they are intended and 70 the line switches 53 both closed thus establishing an electric service to the machine. Closure of a safety switch 52 starts the machine by establishing the starting circuit.

Starting circuit.—From source L1 through line 75 101, pilot fuse, line 102, safety switch 52, line

103, transfer switch 25 (in run position, full lines, Fig. 9), line 104, tub door interlock switch 24, line 105, line 106, line 107, coil of transfer relay, line 108, line 109, line 110, line 111, through safety switch 52, line 112, overload relay contact 5 112', line 113, pilot fuse, line 114 to source L3.

This circuit energizes the coil of the transfer relay effecting opening of the two normally closed contacts and closure of the three normally open contacts which are incorporated in this relay. 10

The closure of the relay contacts establishes additional circuits as follows:

Brake release from source L1 through line 101, pilot fuse, line 102, safety switch 52, line 103, transfer switch 25, line 104, door switch 24, line 15 105, line 106, transfer relay contacts, line 121, line 122, brake coil 23, line 123, line 109, line 110, line 111, safety switch 52, line 112, overload relay contact 112', line 113, pilot fuse, line 114 to source L3. 20

The energizing of the brake coil which is electro-magnetic type releases the brake shoes and maintains the shoes released as long as the circuit through the coil maintains.

Cylinder motor (9) reversing circuit (forward rotation).—From source L1, line 101, pilot fuse, line 102, safety switch 52, line 103, transfer switch 25, line 104, door switch 24, line 105, line 106, contacts of transfer relay, line 131, through contacts A of motor driven reverse drum, line 30 136, line 137, contactor coil E, line 138, line 134, line 135, line 111, safety switch 52, line 112, overload relay contact 112', line 113, pilot fuse, line 114 to source L3. 25

Cylinder motor (9) reversing circuit (reverse rotation).—From source L1, line 101, pilot fuse, line 102, safety switch 52, line 103, transfer switch 25, line 104, door switch 24, line 105, line 106, contacts of transfer relay, line 131, through contacts B of motor driven reverse drum, line 132, 40 line 133, coil F of contactor, line 134, line 135, line 111, safety switch 52, line 112, overload relay contacts 112', line 113, pilot fuse, line 114 to source L3. 35

The effect of these motor reversing circuits is 45 to alternately and at predetermined times cause closure of the forward and reverse contacts which are part of the controller and in this way accomplish reversing of the machine through the reversing of the cylinder drive motor (9). 50

Cylinder motor (9) accelerating circuit.—From source L1 through line 101, pilot fuse, line 102, safety switch 52, line 103, transfer switch 25, line 104, door switch 24, line 105, line 106, through contacts of transfer relay, line 139 to contacts C 55 of motor driven reverse drum, line 140, contactor coil G, line 135, line 111, safety switch 52, line 112, overload relay contact 112', line 113, pilot fuse, line 114 to source L3.

The purpose of the accelerating contactor is to 60 remove from the circuit at predetermined times the reactance in series with the motor windings. This reactance reduces the voltage and consequently the torque of the motor at the moment of reverse and lessens the shock to the machine. 65

The reversing controller disclosed and the transfer relay which is part of this control are old and well known in the art. See patent to R. G. Lockett 1,819,823 dated August 18, 1931 and previous patents. 70

The established circuits, as disclosed, function to maintain the machine in operation until such circuits are interrupted purposely or otherwise, such as by the opening of the safety switch 52, the opening of tub door switch 24 etc. and the cir- 75

cuits outlined represent the normal circuits required by the machine during the normal washing process.

Assuming that the washing operations have been completed and the machine is to be unloaded, the first step required is to dump the washing liquids from the tub and this is accomplished by moving the tub through circuits established as follows:

- 10 **Tub motor dump circuit.**—From source L₁ line 181, pilot fuse, line 182, safety switch 52, line 183, transfer switch 25, line 184, door switch 24, line 181, push button 32, depressed by the operator, line 182, line 183, tub movement limit switch 34, line 184, normally closed push button 41, line 185, line 186, coil D of contactor, line 187, line 188, line 110, line 111, safety switch 52, line 112, overload relay contacts, line 113, pilot fuse, line 114, to source L₃.
- 20 The energizing of the contactor coil D closes the contacts which energize the motor 17 for moving the tub and causes the tub to move through a predetermined arc. As the tub is moved the drain opening moves from the normal position, above the center line of the machine, to an approximate low vertical position and the liquids flow through this opening into the drain underneath the machine.

As soon as the tub starts its dumping movement switch 35 closes so as to establish a circuit for energizing contactor coil D' as soon as switch 189' closes.

When the tub reaches the predetermined point of maximum movement switch 34 is mechanically opened which deenergizes coil D and permits switch 189' to close.

The closure of switch 189' initiates the following circuit, the purpose of which will be given after the circuit is outlined.

- 40 **Tub motor reverse circuit.**—From source L₁ through line 181, pilot fuse, line 182, safety switch 52, line 183, transfer switch 25, line 184, door switch 24, line 185, line 189, normally closed contact 189' of contactor, line 186, switch 35, line 181, normally closed push button 43, line 182, line 183, coil D' of contactor, line 184, line 188, line 110, line 111, safety switch 52, line 112, overload relay contacts, line 113, pilot fuse, line 114 to source L₃.

The effect of the described circuit is to energize the second coil D' of the contactor which closes, establishing circuit to the tub moving motor (17), causing reversal of the direction of rotation of such motor and the return of the tub to its original position with the dump opening again above the center line of the machine.

When the tub reaches this normal position the described circuit is interrupted by the mechanical opening of switch 35.

It will be noted that there is a possibility of the contactors opening due to a momentary opening of a switch in the energizing circuits therefor. To insure continuity of feed to the contactor coils in such a contingency, an auxiliary feed is provided from source L₁ through line 211, such feed being established and maintained only as long as either of the contactors are closed.

The machine is now ready for the withdrawal of the work which has been processed and the next step toward this is the opening of the tub doors manually to provide access to the cylinder within which the clothes were processed. With the tub doors fully opened the tub is rotated to a predetermined dumping position. The circuit through which this is accomplished being:

- 75 **Tub motor unloading circuit.**—From source L₁,

line 181, pilot fuse, line 182, safety switch 52, line 183, transfer switch 25, manually moved to inching position (broken lines, Fig. 9), line 178, switch 26, closed by opening of tub doors, line 171, line 201, contacts of push button 41, depressed by operator, line 205, switch 42, line 206, line 186, coil D of contactor, line 187, line 188, line 110, line 111, safety switch 52, line 112, overload relay contacts, line 113, pilot fuse, line 114 to source L₃.

The establishment of this circuit causes movement over and toward the operator of the tub, such movement continuing as long as the operator maintains push button 41 depressed or until the maximum predetermined movement has occurred when switch 42 is mechanically opened, interrupting the circuit and stopping movement of the tub.

To obtain opposite movement of the tub if needed a second circuit is provided, being:

Tub motor reversing circuit.—From source L₁, line 181, pilot fuse, line 182, safety switch 52, line 183, transfer switch 25, line 178, door switch 26, line 171, line 201, line 202, contacts of push button 43, depressed by operator, line 203, switch 35', line 204, line 183, coil D' of contactor, line 184, line 188, line 110, line 111, safety switch 52, line 112, overload relay contacts, line 113, pilot fuse, line 114 to source L₃.

This circuit closes the contactor which gives reverse movement of tub drive motor 17, such movement continuing as long as the push button is maintained depressed or until the limit of allowable movement is reached at which time switch 35' is opened and stops further movement of the tub.

Having, as indicated in the foregoing, brought the tub to the required position for the unloading of the machine, the next requirement is to move the cylinder and the various pockets thereof to registry with the tub opening and in proper positions for the dumping of the load from the cylinder and the introduction of new work into the cylinder for processing.

As the cylinder disclosed is multi-pocket type this requires the registry of the cylinder through a number of positions and the circuits required are as outlined below.

The opening of the tub doors have mechanically caused the opening of switch 24 and the closure of switch 26 and thereby the interruption of the running circuits and the establishment of the circuits required for inching movement of the cylinder.

The normal movement of the cylinder is over and toward the operator or in a counter-clockwise direction, as shown in Figs. 5 and 7, and the description of the following circuit which refers specifically to the movement of a single pocket, can be assumed as referring to the movement required for the loading of any or all of the pockets as the same circuit is needed for each pocket moved to the unloading and subsequently to the loading positions.

Cylinder unloading circuit.—From source L₁ through line 181, pilot fuse, line 182, safety switch 52, line 183, transfer switch 25, now in inching position, line 178, door switch 26, now closed, line 171, line 172, contacts 31 of drum 21', line 173, contacts of push button 28, depressed by operator, line 174, line 175, normally closed contact of transfer relay, line 177, line 187, coil E of contactor, line 188, line 184, line 185, line 111, safety switch 52, line 112, overload relay contact, line 113, pilot fuse, line 114, to source L₃.

The closure of push button 28 by the operator

energizes the coil of the forward contactor and causes movement of the cylinder drive motor (9) and consequently of the cylinder of the machine in the desired direction, such movement continuing while the operator maintains the push button depressed within the limits fixed by contacts 31 which are normally closed and which open when the cylinder has rotated through the maximum safe movement.

10 The opening of contacts 31 is caused mechanically by the cylinder reaching a fixed point and the circuit is interrupted at this point irrespective of whether the operator maintains the push button depressed or not. The purpose of this 15 being to prevent excessive movement of the cylinder and consequent possible damage to the machine or the goods being discharged from same.

The foregoing of course presupposes the manual opening of the cylinder door before the movement outlined is effected.

The cylinder movement outlined is repeated for as many as there are divisions in the cylinder or until such time as the load is entirely discharged.

25 The next step is then to recharge the cylinder with work to be processed and this is accomplished through the circuit:

Cylinder loading circuit.—From source L1, line 101, pilot fuse, line 102, safety switch 52, line 103, 30 transfer switch 25, line 170, door switch 26, line 171, line 172, contacts 33, line 178, push button 27, closed by operator, line 179, line 180, line 175, normally closed contact of transfer relay, line 177, line 137, coil E of contactor, line 138, line 134, 35 line 135, line 111, safety switch 52, line 112, overload relay contacts, line 113, pilot fuse, line 114 to source L3.

The difference in effect between this circuit and the one immediately preceding is in the fact 40 that a separate set of switches is utilized to prevent cylinder movement beyond a predetermined point, the position in this case differing from the predetermined point established by contacts 31 and fixing the dumping movement limits.

45 In the case of both the circuits for the obtaining of the dumping and loading positions the brake must be released coincident with the energizing of the cylinder drive motor 9 and this is accomplished through the circuit:

50 From source L1, line 101, pilot fuse, line 102, safety switch 52, line 103, transfer switch 25, line 170, door switch 26, line 171, line 172, contacts 30 or 31, lines 173 or 178, push buttons 27 or 28, lines 181 or 186—187, 182, 183, 184, 185, 55 line 122, brake coil 23, line 123, line 109, line 110, line 111, safety switch 52, line 112, overload relay contacts, line 113, pilot fuse, line 114 to source L3.

This circuit for the release of the brake is duplicated to release the brake under the conditions 60 outlined in the following when it is assumed that for pertinent reasons it is desirable to move the cylinder in a direction opposite to that normally used in the dumping and loading cycle.

The circuit through which this cylinder reversal is accomplished is as follows:

From source L1, line 101, pilot fuse, line 102, safety switch 52, line 103, transfer switch 25, line 170, door switch 26, line 171, line 191, push button 29, depressed by the operator, line 192, normally closed contact of transfer relay, line 193, line 133, coil F of contactor, line 134, line 135, line 111, safety switch 52, line 112, overload relay contacts, line 113, pilot fuse, line 114 to source L3.

75 It will be noted from the connection diagram that this circuit energizes the contactor coil F

other than that E used for the normal inching of the cylinder and provides for reverse movement of such cylinder, no provision, however, being included in this circuit for automatic stoppage of the cylinder and therefore such reverse cylinder movement will continue as long as the operator maintains pressure on push button 29. The feature disclosed in the inching circuit, whereby the cylinder automatically stops when reaching a predetermined position, is old in the art and has been disclosed as part of the R. G. Lockett patent and others, referred to in the foregoing. The actual motor circuits are not described in detail as such motor circuits are those commonly used for the operation and reversal of motors and the elements as disclosed are well known in the art.

What we claim is:

1. In a machine of the class described and having a rotatable perforate washing cylinder 20 and a tub therefor, said parts having work-receiving openings registrable for loading and unloading said cylinder, and said tub having a drain opening for discharge of washing fluid, said cylinder being mounted for washing rotation about a horizontal axis, said tub being mounted for adjustment about said axis between a washing position wherein its work-receiving opening extends thereabove, an unloading position wherein its work-receiving opening extends 30 therebelow, and a draining position wherein its drain opening is positioned to discharge by gravity, said drain opening being located relative to said tub work-receiving opening to be above the liquid level in said tub when the latter is in said 35 washing position, power actuating means for said tub and control means for said power means including means actuatable by the operator when said tub is in one of said positions for preselecting another of said positions and for initiating 40 tub movement theretoward, said control means providing means for stopping said power means and terminating said tub movement automatically upon attainment by said tub of its preselected position.

2. In a machine of the class described and having a rotatable perforate washing cylinder, a coaxial cylindrical tub therefor, said parts having work-receiving openings registrable for loading and unloading said cylinder with doors for 50 said openings, said tub having a drain opening for discharge of washing fluid, said cylinder being mounted within said tub for rotation about a horizontal axis, said tub being mounted for adjustment about said axis between positions including a washing position and a draining position, said drain opening being located in said tub for discharge by gravity therefrom when the tub is in draining position and for elevation above the tub liquid level when the tub is in washing 60 position, and stationary closure means cooperative with said drain opening with valve effect, and arranged to register with said drain opening to close the latter when said tub is in said washing position.

3. In a machine of the class described and having a rotatable perforate washing cylinder, a coaxial cylindrical tub therefor, said parts having work-receiving openings registrable for loading and unloading said cylinder, with doors for 70 said openings, said tub having a drain opening for discharge of washing fluid, said cylinder being mounted within said tub for rotation about a horizontal axis, said tub being mounted for adjustment about said axis between a loading 75

and washing position wherein its work-receiving opening extends thereabove, an unloading position wherein its work-receiving opening extends therebelow, and a draining position wherein its drain opening is positioned to discharge by gravity, means for adjusting said tub between its said positions, and stationary closure means cooperative with said drain opening with valve effect, and arranged to register with said drain opening to close the latter when said tub is in said washing position only.

4. In a machine of the class described and having a horizontally disposed washing cylinder, a coaxial tub therefor, said parts being mounted for independent rotation about their axis, said cylinder being within said tub and having radial partitions symmetrically disposed about said axis to provide three compartments, and having, for each compartment, a peripheral opening adjacent the leading partition, when the cylinder is rotating forwardly, and a circumferentially sliding door for said opening, said tub having a work opening at the front of the machine, overlying the path of said cylinder openings, and having a peripheral drain opening at the back of the machine, said tub openings being peripherally located to provide substantially 180° of tub continuity therebetween at the bottom of the machine, for a washing position, means for adjusting said tub about said axis forwardly to a dumping position wherein the lower extremity of its said work opening is 60° below said washing position thereof, and rearwardly to a draining position wherein said drain opening is substantially at the bottom of the tub, means for adjusting said cylinder to a position wherein one of its partitions extends horizontally toward the front of the machine, and means for thereafter advancing said cylinder in steps of 60° each, to provide unloading and reloading positions successively for the several compartments.

5. In a machine of the class described and having a horizontally disposed washing cylinder, a coaxial tub therefor, said parts being mounted for independent movement about their axis, said cylinder being within said tub and having radial partitions symmetrically disposed about said axis to provide three compartments, and having, for each compartment, a peripheral opening adjacent the leading partition, when the cylinder is rotating forwardly, and a circumferentially sliding door for said opening, said tub having a work opening at the front of the machine, overlying the path of said cylinder openings, and having a peripheral drain opening at the back of the

machine, said tub openings being peripherally located to provide substantially 180° of tub continuity therebetween at the bottom of the machine, for a washing position, means for adjusting said tub about said axis forwardly to a dumping position wherein the lower extremity of its said work opening is 60° below said washing position thereof, and rearwardly to a draining position wherein said drain opening is substantially at the bottom of the tub, means for adjusting said cylinder to a position wherein one of its partitions extends horizontally toward the front of the machine, and means for thereafter advancing said cylinder in steps of 60° each, to provide unloading and reloading positions successively for the several compartments, said tub work opening extending peripherally 120° whereby, when said tub is in said dumping position, access may be had to a cylinder compartment which is above the dumping position of said cylinder compartment.

6. In a machine of the class described and having a rotatable perforate washing cylinder and a tub therefor, said parts having work-receiving openings registerable for loading and unloading said cylinder, said cylinder being mounted for washing rotation about its axis, said tub being mounted for adjustment about said axis between a washing position wherein its work-receiving opening extends thereabove and an unloading position wherein its work-receiving opening extends therebelow, power actuating means for said tub and control means for said power means including means actuatable by the operator when said tub is in one of said positions for initiating tub movement toward the other of said positions, said control means providing for terminating said tub movement automatically upon attainment by said tub of its said other position.

7. In a machine of the class described and including a rotatable washing cylinder and a tub therefor adjustable about a horizontal axis to and from a draining position, said tub having a drain opening located to discharge washing fluid when said tub is in said draining position and to be elevated when said tub is in other adjusted positions, means for adjustment of said tub to said draining position, and means for adjusting said tub to another position automatically responsive to its attainment of said draining position.
